Primary Examiner—Caron D. Veynar**[57]****CLAIM**

The ornamental design for a universal radius forming and cleaning tool, as shown and described.

DESCRIPTION

FIG. 1 is a perspective view of the universal radius forming and cleaning tool showing my new design;
 FIG. 2 is a left side elevational view thereof;
 FIG. 3 is a front elevational view thereof;
 FIG. 4 is a right side elevational view thereof;
 FIG. 5 is a rear elevational view thereof;
 FIG. 6 is a top plan view thereof; and,
 FIG. 7 is a bottom plan view.
 FIGS. 5-7 are drawn on an enlarged scale.
